UNITED STATES PATENT OFFICE

CARL C. JANTZ, OF ST. LOUIS, MISSOURI

DESIGN FOR AN AUTOMOBILE RADIATOR ORNAMENT

Application filed May 16, 1930. Serial No. 35,661. Term of patent 3½ years.

To all whom it may concern:

Be it known that I, CARL C. JANTZ, a citizen of the United States of America, residing in the city of St. Louis, in the State of Missouri, have invented a new, original, and ornamental Design for an Automobile Radiator Ornament, of which the following is a specification, reference being had to the accompanying drawing, forming a part thereof.

Fig. 1 is a plan view of an automobile radiator ornament showing my new design.

Fig. 2 is a side elevational view of the same.

I claim:

The ornamental design for an automobile radiator ornament, as shown.

CARL C. JANTZ.
